(57) **CLAIM**

The ornamental design for a multiple spinner carousel for dressing a grinding wheel, as shown and described.

DESCRIPTION

FIG. 1 is a perspective view of a multiple, spinner carousel for dressing a grinding wheel.

FIG. 2 is an opposite view of FIG. 1.

FIG. 3 is an exploded view showing rotatable spinners spaced from the multiple spinner carousel of FIG. 1.

FIG. 4 is an opposite view of FIG. 3.

FIG. 5 is a top view of the multiple, spinner carousel for dressing a grinding wheel of FIG. 1.

FIG. 6 is a bottom view of the multiple, spinner carousel for dressing a grinding wheel of FIG. 1.

FIG. 7 is a front view of the multiple, spinner carousel for dressing a grinding wheel of FIG. 1.

FIG. 8 is a rear view of the multiple, spinner carousel for dressing a grinding wheel of FIG. 1.

FIG. 9 is a side view of the multiple, spinner carousel for dressing a grinding wheel of FIG. 1.

FIG. 10 is an opposite view of FIG. 9; and,

FIG. 11 is a perspective view of the multiple, spinner carousel for dressing a grinding wheel of FIG. 1 attached to a grinding machine adjacent a grinding wheel in accordance with the present teachings.

The broken line showing of portions of a multiple spinner carousel for dressing a grinding wheel is included for the purpose of illustrating environmental structure and forms no part of the claimed design.

1 Claim, 7 Drawing Sheets
